(57) **CLAIM**

The ornamental design for a vent tube for bottling machine, as shown and described.

DESCRIPTION

FIG. 1 is a bottom perspective view of a vent tube for bottling machine in accordance with an embodiment of my new design.

FIG. 2 is a top perspective view of a vent tube for bottling machine in accordance with an embodiment of my new design.

FIG. 3 is a front elevation view of a vent tube for bottling machine in accordance with an embodiment of my new design.

FIG. 4 is a left side elevation view of a vent tube for bottling machine in accordance with an embodiment of my new design.

FIG. 5 is a top view of a vent tube for bottling machine in accordance with an embodiment of my new design; and, FIG. 6 is a bottom view of a vent tube for bottling machine in accordance with an embodiment of my new design.

The rear and right side elevation views are omitted as they are mirror images of the front and left side elevation views, respectively.

The broken lines in the drawings depict portions of the receiver for a bottling machine which form no part of the claimed design.
